UNITED STATES PATENT OFFICE.

ALLAN S. BARROWS, OF LOS ANGELES, CALIFORNIA, ASSIGNOR TO THE YOUNGSTOWN STEEL DOOR COMPANY, OF CLEVELAND, OHIO, A CORPORATION OF OHIO.

METALLIC CAR DOOR.

Application filed November 5, 1925. Serial No. 67,177.

This invention relates to improvements in metallic car doors.

An object of the invention is to provide a fabricated car door structure made up of sheet metal, having a re-enforced body and edge arrangement affording great strength, durability and simplicity in construction, this application being a continuation in part of my prior application, Serial Number 10 486,808, filed May 8, 1919, now Patent 1,560, 526, granted November 10, 1925.

More specifically, the purpose of the invention contemplated herein, is to provide a metallic door made up of a plurality of sheet metal panels provided with strengthening corrugations, together with re-enforcing edge members in the form of rolled sections of angular formation, in which one angular portion is secured to the sheet metal 20 panels in a particular manner, said rolled section at the rear edge of the door co-operating with means upon the panels to provide a spark seal, and the angular section at the bottom of the door being arranged so as to 25 provide one angular portion which may be secured to the panels and which includes another angular portion disposed at right angles to the main plane of the door and arranged to present an efficient bearing member 30 for supporting the door from the bottom for movement with respect to supporting mountings usually provided therefor.

Other and further objects of the invention will more clearly appear from the description and claims hereinafter following.

In the drawings, Figure 1 is a front, elevational view of a car door, made up in accordance with my invention; Figure 2 is a vertical, sectional view of the door substantially on the line 2—2 of Figure 1, with fragmentary views of supporting rollers showing the adaptability of the bottom edge of the door for co-operation with the supporting rollers. Figure 3 is a horizontal, 40 sectional view of the door construction substantially on the line 3—3 of Figure 1. Figure 4 is a vertical, sectional view similar to Figure 2, showing a slightly different embodiment of the invention; Figure 5 is a horizontal, sectional view similar to Figure 3, showing the construction illustrated in Figure 4. Figure 6 is a front, elevational view similar to Figure 1, of a slightly different embodiment of the invention. Figure 7 is a vertical, sectional view of the

door substantially on the line 7—7 of Figure 6. And Figure 8 is a horizontal, sectional view of the door construction on the line 8—8 of Figure 6.

Referring first to Figures 1 to 3, inclusive, the invention contemplates the provision of a metallic door of the usual rectangular form, and which includes a main body portion made up of a plurality of metallic sheet metal panels 10, 11 and 12, said panels having their adjacent horizontal edges overlapped and rigidly connected by welding or by rivets, as indicated at 13. Each of the panels is made of relatively thin sheet metal, and in order to reduce its thickness to a minimum consistent with the necessary strength, each panel is provided with strengthening means, in this instance being shown as horizontally disposed corrugations 14 and adjacent the forward and rear edges 75 of the main body portion, the panels are provided with vertically disposed corrugations 14 and 15, the material of the body portion extending outwardly of the corrugations 14 and 15 to provide marginal sections 16 and 17, the main body portion also extending outwardly of the uppermost corrugation 18 and the lowermost corrugation 19 to provide marginal sections 20 and 21. The vertical corrugations 14 and 15 at their upper and lower extremities preferably merge with the upper and lowermost horizontal corrugations 18 and 19, and the remainder of the horizontal corrugations 14 preferably merge with the vertical corrugations 14 and 15, as shown. 80 The rear top and bottom marginal portions 16, 20 and 21 of the main body portion are flanged in each instance, as indicated at 22, each flange extending inwardly at an angle to the main plane of the door and beyond 85 the inner face thereof, the flange at the rear edge of the door in conjunction with a re-enforcing element hereinafter referred to, being arranged to operate as a spark seal.

Associated with the bottom edge of the 100 main body portion is a combined reenforcing element and supporting member 22^a, which in this instance takes the form of an inverted T bar, the vertical flange 23 of which is secured to the marginal section 21 of the 105 main body portion by welding, or by rivets, as indicated at 23^a. The flange 24 at the inner side of the central flange or stem 23 of the T section, extends beneath the in-turned flange indicated at 22^a at the bottom of the 110

door, and lies against the same. The opposite flange 25 extends outwardly substantially at right angles to the main plane of the body portion and forms part of the lower-
5 most portion of the door, and provides a horizontally extended member adapted to bear upon suitable mounting means such as rollers to support the door from the bottom for operating movement.

- 10 The marginal portion 16 at the rear edge of the door likewise has a T section 26 associated therewith, the stem 27 of said T section being secured to the marginal portion by welding, or by rivets, as indicated
15 at 28, the flange 29 at one side of the stem, extending outwardly substantially at right angles to the main plane of the body portion, and the opposite flange 30 extending inwardly beyond the inner face of the door
20 and lying against the turned flange 22 on the main body portion, the flange 30 and the flange on the body portion co-operating with the usual means associated with the door mountings to form a re-enforced spark
25 seal. The top edge of the door has a T section 31 associated therewith, and the stem of the T section is connected to the marginal portion 20, the flanges of the T section extending to opposite sides of the main body
30 portion in the same manner heretofore described with respect to the bottom and rear edges. The forward edge of the door has an angular member 32 associated therewith, one flange 33 being secured to the outer face
35 of the marginal section 17, and the other flange 34 extending outwardly substantially at right angles to the main plane of the door. The members 22, 26, 31 and 32 are connected at their meeting ends by any suitable means to provide a continuous frame.
40 As before stated, the T section at the bottom of the door serves as a member for supporting the door from its bottom edge upon rollers, such as those indicated at 35, although
45 it is apparent that other means may be utilized adapted to engage the T section at the bottom of the door to support the same for its operative movements.

Referring now to Figures 4 and 5, there is
50 shown a construction which, so far as the main body portion and the T bars are concerned, is identical with that heretofore described, and consequently the same reference characters will be used to designate similar parts in the two constructions, except where otherwise indicated. In conjunction with a door of the character described in connection with Figures 4 and 5, re-enforcing strips are disposed on the inner side of the door
55 and adapted to brace the same in a novel manner. In this connection a strip 36 is shown at the rear edge of the door, which strip is vertically disposed and has its inner edge secured to the body portion of the door
60 inwardly of the corrugation thereof, be-

ing secured by welding, or by rivets, as indicated at 37, the strip bridging or spanning the mouth of the corrugation and having its outer end 38 connected to the marginal section disposed outwardly of the corrugation.
70 The top, bottom and forward edges of the door are provided with re-enforcing strips in identically the same manner, each of which spans the related corrugation and has its inner end portion connected to the main body portion inwardly of the corrugation and has its opposite end portion connected to the main body portion outwardly of the corrugation.
75

Referring now to Figures 6 to 8, inclusive, there is shown still another embodiment of the invention. In this construction sheet metal panels 40, 41 and 42 are shown having their adjacent horizontal edges over-lapped and rigidly connected by welding, or rivets, as indicated at 43, to provide a continuous rectangular body portion. The forward rear, top and bottom edges of the body portion are provided with re-enforcing means of identically similar character, and in this connection it is deemed sufficient to describe the construction at one edge portion and use similar reference characters to designate similar parts of the remaining edge portions of the main body portion. At the bottom edge of the door, the main body portion is provided with an integral portion 44 inclined outwardly from the main plane of the door, the integral portion 44 having thereon an integral extension or continuation 45 which extends substantially parallel with the main plane of the door, and outwardly of said parallel portion, the extension 45 is turned inwardly toward the main plane of the door, as indicated at 46. Secured to the inner face of the main body portion inwardly of the inclined portion 44, by means of welding, or rivets, as indicated at 47, is a re-enforcing strip 48, which extends outwardly of the angular portion 44 and extension 45 is spaced relation with respect thereto, and extends outwardly beyond the turned portion 46 on the extension 45. Associated with the re-enforcing strip 48 and the lower end of the main body portion, is a re-enforcing section 49, which, as shown, is in the form of an angle bar having one flange 50 extending substantially at right angles to the main plane of the door, which flange is secured by suitable means, such as welding, or rivets, to the turned portion 46 on the extension 45, and the other flange 51 of said angle bar extending parallel with the re-enforcing strip 48, and being secured thereto by suitable means, such as welding, or riveting. It will be noted that the flange 50 of the angle bar provides a horizontally disposed bearing member adapted to co-operate with suitable mountings such as the rollers 52 for supporting the door from its bottom for operative
115
120
125
130

- movement. As above stated, the construction at the front, top and forward edges of the door is identically similar to that above described, the angle members being connected together by suitable means to provide a frame. Inwardly of the angularly disposed portions 44 of the door, the main body portion is provided with a plurality of horizontally disposed corrugations 53, said corrugations preferably merging at the forward and rear edges of the door with the hollow tube-like formation provided by the angular portions, re-enforcing strip and associated angle bar.
- 15 While I have herein shown the preferred manner of carrying out the invention, the same is merely illustrative, and I contemplate all changes and modifications which come within the scope of the claims appended hereto.
- 20 I claim:
1. In a car door, the combination with a metallic body member; of a re-enforced edge construction for said body member, comprising an integral angular portion of said main body member turned outwardly of the face of the door away from the main plane of said door, said integral portion having an integral extension extending at an angle to the angular portion and outwardly toward the edge of the door; a re-enforcing strip having its inner edge secured to the main body member inwardly of said angular portion and extending toward the edge of said door in spaced relation with reference to 35 said angular portion and extension; and an angular member having an angular portion spaced outwardly of said angular portion of the main body member and extending substantially normal to the main plane of said door, and another angular portion extending substantially at right angles thereto, said angular member being secured to said extension and to said strip and co-operating therewith to provide a hollow tubular formation.
2. In a car door, the combination with a main body portion composed of sheet metal and having a corrugation extending along one edge thereof with a flat marginal portion 50 outwardly of said corrugation; of means for reinforcing said edge of the door in the form of a T-section having the stem thereof secured to said flat marginal portion and with the flanges extending inwardly and outwardly of the stem, and a strip secured to the main sheet body portion at points inwardly and outwardly of said corrugation and bridging the open mouth thereof.
- 25 30 35 40 45 50 55 60
- In witness that I claim the foregoing I have hereunto subscribed my name this 29th day of October, 1925.

ALLAN S. BARROWS.
